SNOWMOBILE

Anthony MacKeen and Yves Anselme Lapointe, Valcourt, Quebec, Canada, assignors to Bombardier Limited, Valcourt, Quebec, Canada

Filed Oct. 6, 1969, Ser. No. 19,428

Term of patent 14 years

Int. Cl. D12—13

U.S. Cl. D14—24

FIG. 1.

FIG. 2.

FIG. 4.

FIG. 3.

FIG. 1 is a perspective view from the top, and one side of the snowmobile showing our design.

FIG. 2 is a side elevation view thereof.

FIG. 3 is a front elevation thereof.

FIG. 4 is a fragmentary plan view thereof.

The rear panel below the seat is open. The side opposite to that shown is a mirror image thereof.

We claim:

The ornamental design for a snowmobile, as shown and described.
